UNITED STATES PATENT OFFICE.

ELWOOD B. AYRES AND HERMANN BOGATY, OF PHILADELPHIA, PENNSYLVANIA,
ASSIGNORS TO THE PHILADELPHIA TEXTILE MACHINERY COMPANY, OF
PHILADELPHIA, PENNSYLVANIA, A CORPORATION OF PENNSYLVANIA.

DRYING APPARATUS.

1,393,003.

Specification of Letters Patent. Patented Oct. 11, 1921.

Application filed December 1, 1919. Serial No. 341,664.

To all whom it may concern:

Be it known that we, ELWOOD B. AYRES and HERMANN BOGATY, a citizen of the United States and a citizen of Russia, respectively, (the said Bogaty having declared his intentions of becoming a citizen of the United States,) and residents of Philadelphia, Pennsylvania, have invented certain Improvements in Drying Apparatus, of

10 which the following is a specification.

Our invention relates to certain improvements in driers of the type in which the material is carried through a drying chamber and the air is circulated through the drying 15 chamber and through a heating chamber by means of fans, or other devices, so that the material passing through the drying chamber will be properly dried.

One object of our invention is to provide 20 a conveyer of the above type that will carry powdered, or other, material, and, in some cases, liquid, which is to be dried.

Another object of the invention is to provide a pan conveyer and to design the pans 25 so that their edges will overlap in order that a continuous stream of material will flow into the pans without spilling.

A further object of the invention is to provide a conveyer so that the material is 30 carried by both runs of an endless chain.

A still further object of the invention is to provide means for discharging the material from one run to the run next below and to reduce, separate, or crush certain 35 materials as they pass from one run to the other.

The invention also relates to certain details, which will be fully described herein-after, reference being had to the accompanying drawings in which:

Figure 1 is a longitudinal sectional view illustrating our improved drying apparatus;

Fig. 2 is a transverse sectional view on 45 the line 2-2, Fig. 1;

Fig. 3 is an enlarged view, showing the conveyers and the reducing rolls;

Figs. 4, 5 and 6 are views illustrating details of one of the pans and the hangers; 50 and

Fig. 7 is a view illustrating a modification in which a single conveyer is used.

Referring to Figs. 1, 2 and 3 of the drawings, 1 is the casing inclosing a drying

chamber 2 and, in the present instance, two 55 heating members 3, 3—one in each side of the drying chamber. In these heating chambers are coils of steam pipes 4. Fans 5 are located in the partitions between the heating chambers and the drying chambers 60 so as to circulate the air transversely through the heating chambers.

While we have shown a given type of drying apparatus, it will be understood that the invention may be used in different types 65 of apparatus having various methods of circulating air and heating the air in circulation.

6, 6^a are two sets of endless chains. The chains 6 are adapted to pass around sprocket 70 wheels 7 on a driven shaft 8 and around a sprocket wheel 9 at the opposite end of the drier. The chain 6^a is adapted to pass around sprocket wheels 7^a on a driven shaft 8^a at one end of the drier and at the opposite end 75 around a sprocket wheel 9. The chains carry pans 10, which are pivotally suspended from the chains, as clearly shown in Fig. 3. Each pan 10 is attached to a hanger 11 at each side pivoted at 12 to the chains and the 80 hanger at one side has an arm 13 extending above the run of the chain and has a projection 14 below the pan, as shown in Figs. 4 and 5. The distance between the centers of the pivots of the pans is such that when 85 the pans are on the horizontal run, the lip of one pan overlaps and preferably interlocks with the lip of another pan, so that the material, either powder or liquid, discharged into the pans from a continuous 90 flowing chute, will not be spilled, as one after another of the pans passes the chute.

It will be noticed that the pivots 12 for each pan are not attached directly to the chains, but to an arm 16 securely bolted to 95 one of the links 17 of the chain beyond the pivot point, Fig. 6, so that, in passing around curves, as at the left of Fig. 3, the pan is raised in order that its rear lip will disengage the forward lip of the succeeding pan, 100 and, having completed this movement, its forward lip will rest upon the lip of the preceding pan. When the pans pass around the sprocket wheel 7, in the direction of the arrow, the arms 16 will lower the pan 10 so as 105 to disengage its lip from the lip of the succeeding pan and will carry it onto the upper run with its lip under the lip of the pre-

ceding pan so that at all points, except where they pass around the sprocket wheels, one pan overlaps another.

In this drier, it is desirable that the material be discharged from each run of each conveyer and to provide reducing, or crushing, rolls between which the material passes. We provide a hopper 18 directly below the upper run of the conveyer 6. This hopper is located above a pair of reducing rolls 19, and the material after passing between these rolls is discharged directly into the pans 10 on the lower run of the conveyer. In order to discharge the pans on the upper run, we provide cams 20, which are located in the path of the projections 14, so that when a pan strikes this cam it is tilted, as shown in Fig. 3, and its contents discharged into the hopper 18. When the pan passes the cams it gradually assumes its horizontal position, being empty, and is not filled until it passes under the reducing rolls 19.

When the material is discharged into the pan from the hopper it has been thoroughly mixed and reduced and will be carried by the pans onto the lower run of the conveyer 6 until it reaches a discharge point, where a cam 21 is located in the path of the upper projecting arms 13 of the pan and the contents of the pan will be discharged into another hopper 18^b under which are reducing rolls 19^a. The material passes between these rolls into the pans on the lower run 6^a of the conveyer, and the above operation is repeated.

The lowest rolls 19^b, in the present instance, are the crushing rolls, but it will be understood that the type of roll may be modified, depending upon the material being dried.

In Fig. 1, we have shown two endless belt conveyers, but it will be understood that a single conveyer may be used, as shown in Fig. 7, or more than two belts may be used, if desired, and the material may be discharged directly from the lower run of the lower conveyer into a hopper, or may pass through final crushing rolls, as illustrated in Fig. 1, and into a hopper 22, which may discharge the material into any suitable conveyer, or receptacle.

In the present instance, we have shown a feeding hopper 24 having an inclined chute 25, which deposits material onto the upper run of the conveyer 6. In this hopper is a feed wheel 26, which can be driven at any speed desired so as to increase or diminish the amount of material discharged from the spout onto the conveyer.

It will be seen by the above construction that we are enabled to carry material through a drying chamber by means of pans and to discharge the material from the pans from an upper run to the lower run of the same conveyer, or from the lower run of one con-

veyer to the upper run of another conveyer so that both runs of the conveyer carry material. This material is subjected to the drying action of currents of heated air passing transversely through the drying chamber. The crushing rolls, or reducing rolls, may be located under one or more, or all of the hoppers, if found desirable. Where material is being dried that does not require reducing, when the hopper may be so shaped as to direct the material from the pans of the upper run to the pans of the lower run directly below it.

In Fig. 7 we have illustrated a single conveyer 6^b having pans hung therefrom in the manner shown in Fig. 3. In this instance, the material is carried through the drying chamber without being discharged from one run to another, being only discharged when dried, into a hopper 22^a from which it is removed from the machine. The feeding device 26^a is a variable feed so as to regulate the amount of material passing to the drier. One or more discharge devices may be used where the material has a tendency to cake or form lumps and reducing rolls may also be used to break up the cakes and lumps, if found desirable.

We claim:

1. The combination in a drying apparatus, of a drying chamber; an endless chain conveyer therein; pans pivoted to the conveyer and hung below the chain, each pan having a lip at each end shaped so that the lip of one pan will interlock with the lip of an adjoining pan; means at each end for discharging the pans; means for releasing the lip of one pan from that of an adjoining pan; and means for feeding material to the pans.

2. The combination in a drier, of a drying chamber; conveyers extending throughout the length of the drying chamber; frames pivotally connected to the conveyers; pans carried by the frames, each pan having a lip at each end so that when the pans are traveling in a horizontal plane the lip of one pan will overlap that of another pan; means for discharging the pans at each run of the conveyer; hoppers for receiving the material and guiding the material from an upper run to a lower run; and means for feeding material to the pans.

3. The combination in a drying apparatus, of a drying chamber; means for circulating heated air through said chamber; a series of endless chain conveyers, one located above another; pivoted carriers having pans, said pans being hung below the chains in a horizontal position, the carriers having upper and lower projections; cams on the upper run in the path of the lower projections; cams on the lower run in the path of the upper projections; hoppers at each end of the drier, one hopper being located be-

tween the upper and lower runs of a conveyer, the hoppers at the end being located between the conveyers, said hoppers being arranged to receive material from one conveyer and to direct it onto the pans of a run directly below it.

4. The combination in a drier, of a drying chamber; a conveyer having a series of pivoted pans arranged to travel in a series 10 of runs, one directly below another; reducers between the several runs, one reducer being at one end of the drier and the other at the opposite end thereof, the pans on one run

of the conveyer traveling in one direction and the pans on the other run traveling in 15 the opposite direction so that material carried by an upper run will be discharged through a reducer onto a lower run and will be carried by the said lower run to the opposite end of the machine where it will 20 be discharged through another reducer onto a run directly below it, traveling in the opposite direction.

ELWOOD B. AYRES.
HERMANN BOGATY.
